UNITED STATES PATENT OFFICE.

WILLIAM C. SHINN, OF LINCOLN, NEBRASKA.

FOLDING LADDER.

1,233,717.

Specification of Letters Patent. Patented July 17, 1917.

Application filed March 1, 1916. Serial No. 81,300.

To all whom it may concern:

Be it known that I, WILLIAM C. SHINN, citizen of the United States, residing at Lincoln, in the county of Lancaster and 5 State of Nebraska, have invented a certain new and useful Improvement in Folding Ladders, of which the following is a full, clear, concise, and exact description.

My invention relates to improvements in 10 folding ladders.

The general object of the invention is to provide an improved and simplified device of this character and one which may be economically manufactured and used in a convenient manner.

In the accompanying drawings I have illustrated several embodiments of the invention.

Figure 1 is a side elevation of one form 20 of ladder showing the same hooked over the comb of the roof of a building.

Fig. 2 is an enlarged view of the upper end of the ladder shown partly in section.

Fig. 3 is an enlarged top plan view of 25 Fig. 1, parts thereof being broken away.

Fig. 4 is a section on the line 4—4 of Fig. 3.

Fig. 5 shows the ladder used as a fire escape.

Fig. 6 shows a modified form of releasing device.

Fig. 7 is an enlarged side elevation of the upper portion of the ladder, parts being broken away.

Fig. 8 is a section on the line 8—8 of Fig. 7.

The ladder in the form illustrated is made entirely of metal, although certain of the structural advantages may be obtained without necessarily using this material throughout.

The ladder is supported by a pair of hooks 1 preferably stamped from heavy sheet metal, said hooks having openings in 45 their lower ends which receive loosely a tubular cross bar 2, and about which they may turn. Said hooks are held in fixed, spaced relation by a rod 3, the projecting ends of which may be riveted over, as shown in Fig. 7, or said rod may project at both ends for purposes hereinafter described, as shown at 4 in Fig. 3. A tilting member or lever 5 is also loosely mounted on the tubular rod 2, preferably at some point between the two 50 hooks. One end of said lever has an opening to which the end of a rope 6 may be se-

cured for the purpose of rocking the hooks with respect to the rest of the ladder in order to release the ladder from its support, as explained later. While the lever 5 is shown 60 in the drawings as of angular construction, it is obvious that the same may be made in any other suitable form if desired.

The ends of the tubular rod 2 are each provided with a slot 7 through which passes 65 the upper link 8 of a metal chain 9. Said upper link is expanded to circular outline and held within the tubular rod by means of a metal stud 10, kept in place by a small pin or rivet 11.

At suitable intervals along the chain, cross bars or rungs 12 are arranged, each being stamped from sheet metal and bent over to substantially the form of an inverted channel, as shown in Fig. 5. The tread is made 75 as wide as necessary. The ends of the channel are contracted to fit loosely over opposite sides of one of the links, and a rivet or other suitable fastening device 13 passes through alined openings in said contracted 80 ends and through the opening in the link. The upper part of the channel is cut away at opposite ends at the point 14, so as not to interfere with the chain and so as to facilitate the drawing together of said ends. 85

The ladder, as thus far described, is made entirely of metal, preferably galvanized iron, to prevent rusting, although I do not limit myself to this material. It is strong and durable, and may be readily rolled or 90 folded into small compass, and conveniently carried about.

It has proved particularly advantageous in the installation of lightning rods on houses and barns, since it may be easily 95 carried about from farm to farm in a wagon or automobile of the agent making the installation. It is fastened in position on the house as follows:

The workman first throws over the house 100 15 the rope 6 which he pulls down on one side thereby drawing up the ladder on the other side. During this operation, the hooks are thrown back about in the position shown in full lines, in Fig. 2, so that as the 105 ladder is drawn upwardly along the sloping roof, the hooks 10 cannot interfere with such movement. The workman continues to pull on the rope until after the hooks have passed the comb of the roof, the pull 110 at this time being directed downwardly along the opposite sloping side of the roof,

whereupon the hooks fall forward into their normal position as indicated in dotted lines, except that they do not engage the roof securely until the lower end of the iron ladder is drawn downwardly, causing the hooks to engage the comb of the roof as shown, in which position the workman may safely entrust his weight to said ladder. After the lightning rod installation has been completed, the operator descends the ladder in the usual manner and passing to the opposite side of the house or barn, pulls downwardly on the rope 6, thereby causing the hooks to rotate about their pivotal support 2 and throwing them back approximately to the full line position; whereupon by slackening off on the rope, the ladder will slide down the inclined roof and may be lowered to the ground. As shown in Fig. 2, the swinging of the hooks is effected by the lever 5, the lower arm of which is preferably positioned at an angle with respect to the other arm to facilitate the swinging movement. The same result may be obtained however, by simply having the rope tied to cross bar 3, first passing it around the tubular member 2, as shown in Fig. 6. The projecting ends 4 of the cross bar 3 limit the backward throw of the hooks by engaging the links of the chain, thereby preventing more than a half revolution of said hooks. With this arrangement, it is necessary in drawing the ladder into position to tie the rope first around the tubular bar 2 with the hooks drawn back so that they will not catch during the upward movement of the ladder, but leaving them free to swing forward and engage the roof after the crest has been passed. When the operator is ready to descend, it is necessary to untie the rope from the bar 2 and tie it to the bar 3, as in Fig. 6. To eliminate the tying and untying operation, the end of the rope may be provided with a suitable hook, if desired. Of course I do not limit myself to a rope, as various other expedients may be adopted.

The ladder is of course applicable to many uses other than the particular one described herein. For example, it may be used as a fire escape, as shown in Fig. 5, by catching

the hooks over the window sill 16. Under such conditions, the release of the ladder is of no particular importance.

It is obvious that the invention is not limited to the particular structural details disclosed herein, except where limitations are imposed in the appended claims.

What I claim as new and desire to secure by Letters Patent of the United States is:

1. In combination, a ladder, a device pivoted to or near the upper end thereof adapted to hook over or engage a support, and a flexible member so connected to said pivoted device and said ladder as to have a reactionary effect upon said ladder, so that a pull upon said member, will tend to throw back said device with reference to said ladder.

2. A ladder comprising a pair of flexible longitudinal members, a transverse member connecting said flexible members at one end thereof, engaging means supported by said transverse member and rotatable with respect to said flexible members, and a flexible releasing member so connected to said engaging means as to rock the latter to an operative position when said releasing member is pulled in a direction opposite to the pull due to the weight of the ladder.

3. A folding ladder comprising a pair of longitudinal members, a cross bar to which said longitudinal members are secured, a plurality of hooks pivotally mounted on said cross bar, a cross rod mounted above said cross bar and engaging said hooks to hold the same in fixed relation and to cause them to revolve together about said cross bar, and a lever mounted for rotation on said cross bar, one arm of said lever cooperating with said cross rod, the other arm thereof being free and adapted to receive operating means, whereby said hooks may be rotated.

In witness whereof, I hereunto subscribe my name this 21 day of February, A. D. 1916.

WILLIAM C. SHINN.
